(57) **CLAIM**

An ornamental design for a flight safety vest for a lap child, as shown and described.

DESCRIPTION

FIG. 1 is a front perspective view of a flight safety vest for a lap child;

FIG. 2 is a front elevational view of the flight safety vest of FIG. 1;
FIG. 3 is a rear elevational view of the flight safety vest of FIG. 1;
FIG. 4 is a right-side elevational view of the flight safety vest of FIG. 1;
FIG. 5 is a left-side elevational view of the flight safety vest of FIG. 1;
FIG. 6 is a top view of the flight safety vest of FIG. 1;
FIG. 7 is a bottom view of the flight safety vest of FIG. 1;
FIG. 8 is a front perspective view of the flight safety vest of FIG. 1 positioned on an unclaimed lap child;
FIG. 9 is a front perspective view of a flight safety vest for a lap child;
FIG. 10 is a front elevational view of the flight safety vest of FIG. 9;
FIG. 11 is a rear elevational view of the flight safety vest of FIG. 9;
FIG. 12 is a right-side elevational view of the flight safety vest of FIG. 9;
FIG. 13 is a left-side elevational view of the flight safety vest of FIG. 9;
FIG. 14 is a top view of the flight safety vest of FIG. 9;
FIG. 15 is a bottom view of the flight safety vest of FIG. 9;
FIG. 16 is a front perspective view of a flight safety vest of FIG. 9 for a lap child;
FIG. 17 is a front elevational view of the flight safety vest of FIG. 16;
FIG. 18 is a rear elevational view of the flight safety vest of FIG. 16;
FIG. 19 is a right-side elevational view of the flight safety vest of FIG. 16;
FIG. 20 is a left-side elevational view of the flight safety vest of FIG. 16;
FIG. 21 is a top view of the flight safety vest of FIG. 16;
FIG. 22 is a bottom view of the flight safety vest of FIG. 16;
FIG. 23 is a front perspective view of the flight safety vest of FIG. 16 positioned on an unclaimed lap child;
FIG. 24 is a front perspective view of a flight safety vest for a lap child;
FIG. 25 is a front elevational view of the flight safety vest of FIG. 24;
FIG. 26 is a rear elevational view of the flight safety vest of FIG. 24;

(Continued)

FIG. 27 is a right-side elevational view of the flight safety vest of FIG. 24;

FIG. 28 is a left-side elevational view of the flight safety vest of FIG. 24;

FIG. 29 is a top view of the flight safety vest of FIG. 24; and,

FIG. 30 is a bottom view of the flight safety vest of FIG. 24.

All of the broken lines shown in the drawings show unclaimed subject matter only and form no part of the claimed design.
